COMBINED HAIR ROLLER AND ADJUSTABLE HAIR HOLDING BAND

George Gebhart, Seminole, Fla., assignor to Consolidated Foods Corporation, Chicago, Ill.

Filed Oct. 7, 1971, Ser. No. 137,592

Term of patent 7 years

Int. Cl. D28—03

U.S. Cl. D86—10

FIG. 1

FIG. 2

FIG. 3

FIG. 4

FIG. 1 is a perspective view of a combined hair roller and adjustable hair holding band showing my new design;

FIG. 2 is a side elevational view thereof; the adjustable band being in a closed position; the side opposite being identical thereto;

FIG. 3 is an end elevation as seen from the left of FIG. 2; and

FIG. 4 is an end elevation as seen from the right of FIG. 2.

I claim:

The ornamental design for a combined hair roller and adjustable hair holding band, as shown and described.
